UNITED STATES PATENT OFFICE.

JOSEPH C. POTI AND HERMAN R. ERDMANN, OF MILWAUKEE, WISCONSIN.

BUILDING BLOCK.

1,412,573.

Specification of Letters Patent. Patented Apr. 11, 1922.

Application filed June 15, 1920. Serial No. 389,097.

To all whom it may concern:

Be it known that we, JOSEPH C. POTI and HERMAN R. ERDMANN, both citizens of the United States, and residents of Milwaukee, in the county of Milwaukee and State of Wisconsin, have invented certain new and useful Improvements in Building Blocks; and we do hereby declare that the following is a full, clear, and exact description thereof.

10 Our invention relates to new and useful improvements in building units such as the usual hollow concrete or tile blocks generally in use as a material for constructing dwellings and other buildings.

15 It is one important object of our invention to provide a simply constructed building block which can be inexpensively made of concrete and the like, and which will have a very effective means for retaining the several blocks forming a wall against possible longitudinal or transverse shifting.

20 A further important object of the invention is to provide a building block having means in one or more of its exposed faces, whereby when a number of such blocks are associated together in the form of a wall, an extremely effective binding may be obtained therebetween.

25 Still another object of the invention is to provide a ventilated building block having means for association with the ventilating opening of adjacent blocks which will prevent the plurality of blocks forming a wall from shifting with respect to each other.

30 With these general objects in view, the invention resides in the novel features of construction, combination and arrangement of parts which will be hereinafter more particularly described and claimed.

35 In the accompanying drawings,

Figure 1 represents an elevational view of a portion of one corner of a building wall fashioned of our improved blocks.

Figure 2 is a plane view of the corner portion of an unfinished wall.

Figure 3 is a longitudinal sectional view taken substantially on the plane of the line 3-3 of Figure 2.

Figure 4 is a vertical transverse section on the plane of the line 4-4 of Figure 3, and

Figure 5 is a perspective view of a slightly modified form of building block having all of the features shown in the other blocks represented in Figures 1 to 4, together with certain additional features.

In using our improved block, various dif-

ferent arrangements may be employed in assembling the same, and also changes may be made in the form and proportions and in the minor details of construction without departing from the principles of the invention or sacrificing any of the important advantages. For instance, in Figure 2 is shown a corner block which is slightly different from the ordinary intermediate wall blocks, while in Figure 5 is depicted a block somewhat different from the other illustrated embodiments of the invention.

Referring more particularly to these drawings, it will be seen that we may construct a wall of any suitable size and shape with a number of our improved blocks 1, each of which is substantially rectangular and is provided with a longitudinally extending substantially rectangular recess 2 opening through the top and bottom thereof. As indicated in Figure 3 the several recesses in the plurality of blocks 1 forming the wall are not aligned, but there is communication therebetween so that proper ventilation may be procured. Each of the blocks 1 has a vertically extending centrally located tongue 3 at one end, and in a similar position at the other end is provided a vertical channel 4.

The tongues 3 and channels 4 are of a corresponding size and shape, and when the blocks are assembled the tongue of one of the same is located in the channel of the next adjacent block in the same horizontal row. However, when an end or corner block 1' is used, the usual end channel is omitted and instead is formed in one of the side walls as shown at 4' in Figure 2. Thus the ordinary formation of the outer exposed face of the wall may be similar throughout the surface thereof.

Each end of the recess 2 is provided with upstanding lugs 5, these lugs projecting above the upper surface of the block a sufficient distance to effectively co-operate with the faces of the recesses in the adjacent blocks when the plurality of said blocks are assembled. Obviously if it is considered necessary or desirable, these lugs may depend from the bottoms of the blocks, or in assembling the same, said blocks may be inverted.

Likewise each of the blocks 1 and 1' has its outer exposed face provided at each corner with a rabbet 6, in other words these rabbets extend around the entire outer exposed face of the block as shown in Figure

- 5, and if necessary the inner exposed face may be similarly provided with rabbets 7. These rabbets are of such a shape that when two or more blocks are assembled, they co-
5 operate to form a dovetail channel in which a suitable plastic binding material 8 may be forced, such material when hardened providing an effective seal and a means for preventing shifting of the different blocks.
10 Inasmuch as it is desirable to coat the outer and inner surfaces of the building wall, said surfaces are roughened or provided with small horizontally extending grooves 9. In other words, these surfaces are so formed
15 as to provide the necessary adhesion between the same and the covering material, such as stucco or the like on the outer surface and plaster on the inner surface.
When the plurality of blocks are assembled
20 as shown in Figures 1, 2, 3 and 4, the tongues 3 will be located in their respective channels 4 and the lugs 5 in the adjacent recesses 2 of the blocks in the next higher row. Under ordinary circumstances the tongues and
25 grooves would prevent lateral shifting of the blocks, but the provision of the lugs in co-operation with the ventilating recesses provide a still further improvement in the wall. And, in addition to these features the
30 dovetail binding between the corner portions of each of the blocks provides a structure which will be a very great improve-

ment over the usual wall formed of concrete or other composition building blocks, and it is also to be noted that the present improved 35 blocks may be constructed and assembled at a cost which is no greater than the average similar blocks.

We claim:

As a new article of manufacture, a rectangular building block, having a vertical opening therethrough and having a rabbet around the periphery of one of its faces, longitudinal grooves connecting the rabbets, lugs projecting upwardly at each end of the opening, the lower portions of the end surfaces of the lugs being disposed in a perpendicular plane and meeting the upper surface of the block in a line which is in the same plane as the side faces of the opening whereby 50 when the blocks are laid in staggered relation the lugs of each block will project into the opening in the block above and center said block so that the adjacent rabbets of two contiguous blocks will register to form 55 a dovetail to receive plastic building and surfacing material.

In testimony that we claim the foregoing we have hereunto set our hands at Milwaukee, in the county of Milwaukee and State 60 of Wisconsin.

JOSEPH C. POTI.
HERMAN R. ERDMANN.
